(57) **CLAIM**

The ornamental design for a cable connector as shown and described.

DESCRIPTION

FIG. 1 is a top perspective view of a cable connector showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion marked as 9 in FIG. 7; and,

FIG. 10 is an enlarged view of portion marked as 10 in FIG. 8.

The dash-dash broken lines in the drawings depict portions of the cable connector that form no part of the claimed design. the dot-dash-dot broken lines in the drawings depict boundaries of the enlargement that form no part of the claimed design.

1 Claim, 10 Drawing Sheets
